UNITED STATES PATENT OFFICE.

JAMES P. HARRISON, OF DANVILLE, VIRGINIA.

GAME-BOARD.

SPECIFICATION forming part of Letters Patent No. 636,663, dated November 7, 1899.

Application filed October 11, 1897. Serial No. 654,773. (No model.)

To all whom it may concern:

Be it known that I, JAMES P. HARRISON, a citizen of the United States, residing at Danville, in the county of Pittsylvania and State 5 of Virginia, have invented certain new and useful Improvements in Game-Boards; and I do declare the following to be a full, clear, and exact description of the invention, such as will enable others skilled in the art to which

10 it appertains to make and use the same, reference being had to the accompanying drawings, and to the figures of reference marked thereon, which form a part of this specification.

15 My object is to provide a game-board of novel construction, especially adapted for the playing of duplicate whist, which will be equipped with a set of card-trays disposed in a novel manner in such compact arrangement that they will be out of the way of the

20 players when not in use.

A further object is the provision of a card-tray, to be used in playing duplicate whist, which will be provided with novel means for indicating the proper disposition of the cards 25 and the "lead" hand in the original and duplicate plays.

A still further object is to provide a game-board, for use in card-playing, having an improved trump-indicator.

30 Another object is the provision of a game-board of improved construction adapted for use in playing the games of backgammon, checkers, chess, and duplicate whist.

With the foregoing and other objects in 35 view the invention consists of a game-board comprising certain improved features and novel combinations of parts, more fully described hereinafter and pointed out in the claims.

40 In the accompanying drawings, Figure 1 is a perspective view of my game-board when folded; Fig. 2, a plan view of the board when open, showing some of the card-trays pulled out. Figs. 3 and 4 are detail views of a card-tray; and Figs. 5, 6, and 7 are detail views of the hinge, counter, and abacus, hereinafter described.

The game-board proper consists of two sections 1 and 2, hinged together and provided 45 with a checkered surface 3 on one side and the backgammon-board 4 on the other side.

If desirable, the board may be constructed

of a single piece, or suitable fasteners 4' are employed to hold the sections together when folded.

The four sides of the board, provided with supporting-legs, are designated by the letters "N," "E," "S," and "W," (shown at 5,) to indicate the different players when the board is used in playing duplicate whist. 55 60

An abacus or counter 6, having thirteen beads, is located in a groove in the face of one of the board-sections and is employed for counting the number of points made by the sets of players when a game of duplicate whist 65 is in progress, the letters "N" and "S" and "E" and "W," respectively, being located at the ends of the groove. When a point is gained, a bead is moved to one or the other end of the groove, as the case may be. The 70 central bead 7 is preferably colored differently from the others.

Opposite corners of the board have circular countersinks 8, and the bottoms of the countersinks have the card-suit designations, 75 such as "clubs," "spades," &c. Disks 9 are pivoted centrally in the countersinks at 10 and have a quadrant cut out at 11 to expose one suit designation at a time. These devices constitute trump-indicators, whose manner of operation is obvious. The remaining corners of the board have dovetail grooves 12, which receive score-cards 13. The score-cards when thus arranged are in convenient position, and yet not in the way of the players, and they 85 can be removed and replaced by others when necessary.

My improved card-trays, employed when duplicate whist is being played, are shown at 14 and are arranged in banks of six at opposite sides of the board, each bank being composed of three sets of two each. These trays slide in and out of the board-sections 1 and 2 like drawers, being provided with pulls or knobs 15 to facilitate their insertion and removal. This arrangement of trays in relation to the board is highly advantageous, as they are always ready for use, and yet never in the way of the players, while they are always with the board and are carried with it 90 from place to place. Each tray has four shallow compartments 16, defined by longitudinal and cross partition-strips 17 and adapted to contain one-quarter of a pack of cards or a 95 100

single "hand." Finger-notches 18 are made in the edges of the tray to facilitate the removal of the cards, and at the front and rear of the tray are semicircular retaining-plates 19, which hold the cards in the compartments. 5 A leaf-spring 20, having one end secured to the tray and the other end free, is adapted to bear against the board-section when the tray is shoved in and retain it. At the meeting-10 point of the partition-strips is a circular indicator plate or disk 21, which also serves as a card-retainer, and it is provided with a central circular countersink 22. A disk 23, similar to disks 9, is pivoted in the countersink. 15 The letters "N," "E," "S," and "W" are printed on disk 21 over the compartments having printed in their bottoms the letters "W," "N," "E," and "S," respectively, and these latter letters indicate that on the "duplicate" play "W's" original hand is placed in the compartment marked "W" in its bottom. 20 The trays are numbered from 1 to 12, respectively, and the number of the tray, together with the letters "A," "B," and "X," 25 is printed in the bottom of the countersink 22. A hand or indicator 24 is printed on the disk 21, and in trays 1, 5, and 9 it points to "N," in trays 2, 6, and 10 it points to "E," for trays 3, 7, and 11 it points to "S," and 30 for trays 4, 8, and 12 it points to "W." This hand indicates the player who has the lead in the "original" hand. On the duplicate play, "E" plays "N's" hands and the duplicate lead is indicated by an arrow 25 on disk 35 21, which arrow on trays 1, 5, and 9 points to "E," to "S" on trays 2, 6, and 10, to "W" on trays 3, 7, and 11, and to "N" on trays 4, 8, and 12. As an additional means of indicating the lead, the letters "A" and "B" are 40 employed. The letter "A" is located beneath that letter on disk 21 which indicates which player is to lead originally, while "B" is beneath the letter indicating who the leader on the duplicate play will be. For instance, on 45 tray No. 1 the letter "A" is beneath "N" on disk 21 and the letter "B" beneath "E" on the disk. When the hands have been played, both original and duplicate, the letter "X," exposed by the disk 23, indicates that the 50 hand in that tray has been finished. On the front of the tray, on opposite sides of the knob or pull 15 thereof, are the letters "A" and "B," respectively. Two slides 26 and 27 are located on the tray-front and are 55 adapted for manipulation to cover the letters "A" and "B." When the game is begun, the slides 26 on all the trays are drawn back, exposing the letters "A." When any tray is 60 played on the original play, the slide 27 is moved to disclose the letter "B" and the slide 26 is closed to hide letter "A," and after the duplicate play has been made the slides are closed, covering both letters "A" and "B" and indicating that the tray is not to be 65 used again.

The trays are played and replaced indiscriminately, and hence the players cannot

tell which hand is being played until the hand has been played, whereupon the disk 23 is turned, exposing the tray-number, and the 70 points having been scored the tray is replaced in the board.

It is desirable to employ trays or drawers 28 underneath the score-cards to hold additional score-cards, so that a quantity will always be at hand for use. Trays 29 are also provided and are employed to hold additional packs of cards, checkers, chessmen, &c. While my game-board is especially adapted 75 for playing the game of duplicate whist, it also serves as a convenient checker and chess board, affording, as it does, means for holding the necessary paraphernalia and for scoring the games.

Many slight changes could be resorted to in 85 carrying out my ideas, and hence I consider myself entitled to all such modified constructions as come within the spirit and scope of the invention.

Having thus described my invention, what 90 I claim as new, and desire to secure by Letters Patent, is—

1. The combination with a game-board, made in two sections hinged together and adapted for backgammon and checkers, said 95 board having deepened or widened edges tray or drawer openings in said edges, of individual card-trays removably received in said openings and each tray or drawer provided with several card-compartments to hold a 100 hand or quarter of a deck of cards.

2. An indicator consisting of a backing or plate having a countersink and circularly-arranged characters located at a quadrant's distance apart on the bottom of the counter-sink, in combination with a disk fitted into the countersink and pivoted centrally which has a quadrant cut therefrom to expose one character at a time, substantially as described. 105

3. A card-tray for use in playing duplicate 110 whist, having card-compartments designated by symbols or characters to indicate the players, which characters are hidden when the cards are in place, and an indicator bearing symbols or characters similar to those designating the compartments and arranged, 115 respectively, adjacent the compartments next those of which their characters are duplicates, substantially as described.

4. A card-tray for use in playing duplicate 120 whist, having card-compartments arranged substantially in the form of a square and having symbols or characters on their bottoms to indicate the players, which symbols are hidden when the cards are in the compartments, and an indicator consisting of a 125 plate having portions located adjacent the corners of the compartments and bearing exposed symbols or characters similar to those designating the compartments and arranged 130 respectively, adjacent the compartments next those of which their characters are duplicates, substantially as described.

5. A card-tray for use in playing duplicate

whist, having card-compartments designated by symbols or characters to indicate the players, which characters are hidden when the compartments are occupied, an indicator bearing symbols or characters similar to those designating the compartments and arranged, respectively, adjacent the compartments next those of which their characters are duplicates, means for indicating the original and duplicate leads, an indicator bearing the number of the tray and characters denoting the orig-

inal and duplicate leads, and a character denoting that the tray has been played through, and a movable device covering the characters last named and adapted to expose one of 15 them at a time, substantially as described.

In witness whereof I affix my signature in presence of two witnesses.

JAMES P. HARRISON.
